Primary Examiner — Rhea Shields(74) *Attorney, Agent, or Firm* — Birch, Stewart, Kolasch & Birch, LLP(57) **CLAIM**

The ornamental design for a brush for body cleansing apparatus, as shown and described.

DESCRIPTION

FIG. 1 is a front, right side perspective view of a brush for body cleansing apparatus showing our new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a perspective view thereof, and shown in an environment.

In FIG. 9, the broken lines are for the purpose of illustrating environment only that form no part of the claimed design.

1 Claim, 5 Drawing Sheets(56)
